Geo. P. Kimmel.

ATTORNEY.

UNITED STATES PATENT OFFICE.

CLARENCE E. BURK, OF MARION, OHIO, ASSIGNOR OF ONE-HALF TO THE VAN ATTA HARDWARE COMPANY, OF MARION, OHIO, A CORPORATION OF OHIO.

RADIO SPEAKER OR HORN.

Application filed July 2, 1926. Serial No. 120,138.

This invention relates to a radio speaker or horn, designed primarily for use in connection with radio receiving sets, but it is to be understood that a speaker device, in accordance with this invention, can be employed in any connection for which it is found applicable, and the invention has for its object to provide, in a manner as hereinafter set forth a long column speaker formed throughout of wood of a non-resonant type for reproducing the bass or deep notes approximately the same as the true tone thereof.

A further object of the invention is to provide, in a manner as hereinafter set forth, a radio speaker or horn device including a structure formed throughout of non-resonant wood to provide a coiled column or tone chamber gradually increasing in diameter from its intake to its outlet for reproducing a sound received by and transmitted from a receiving set in a tone approximately the same as when originally broadcasted.

Further objects of the invention are to provide a radio speaker or horn, in a manner as hereinafter set forth, which is simple in its construction and arrangement, strong, durable, compact, thoroughly efficient in its use, and comparatively inexpensive to manufacture.

With the foregoing and other objects in view, the invention consists of the novel construction, combination and arrangement of parts as hereinafter more specifically described, and illustrated in the accompanying drawings wherein is shown an embodiment of the invention, but it is to be understood that changes, variations and modifications can be resorted to which fall within the scope of the claim hereunto appended.

In the drawings wherein like reference characters denote corresponding parts throughout the several views:

Figure 1 is a vertical sectional view taken between the longitudinal median and one side of the device.

Figure 2 is a view similar to Figure 1 taken between the longitudinal median and the other side of the device.

Figure 3 is a horizontal sectional view on line 3—3 Figure 1.

Figure 4 is a section on line 4—4, Figure 3.

Referring to the drawings in detail 1 55 denotes a rectangular base board or member

of the desired width and length. The base board 1 is constructed of wood of a non-resonant type and the other elements of the device are also constructed of the same material. As to wood of a non-resonant type, any wood possesses such a characteristic if it is of a thickness of a half inch or more, preferably the wood employed should be five-eighths of an inch in thickness. Secured upon the upper face of the member 1 at 60 each end thereof is a radius block and the said blocks are indicated at 2, 3. The length of the block 2 is the same as the width of the member 1 and the outer side edge of the block 2 is flush with an end edge of the member 1. The end edges of the block 2 are flush with the side edges of the member 1. The block 2 has its inner side formed with a concave cutout portion having the wall 4 thereof extend upon an arc through- 65 70 75 80 85 90 95 100 105 110

The block 3 has its outer side edge flush with the other end edge of the member 1 and said block 3 has its end edges 5, 6 disposed at an inclination and extending in opposite directions with respect to each other. The block 3 gradually increased in length from its outer side edge towards its inner side edge. The end edge 6 of the block 3 is spaced from a side edge of the member 1, but positioned in close proximity therewith. The end edge 5 of the block 3 is positioned a substantial distance from the other side edge of the member 1 and the distance between the end edge 5 of the block 3 and the 115 said side edge of the member 1 is greater than the distance between the end edge 6 of the block 3 and the other side edge of the member 1. The block 3 is of materially less length than the length of the block 2. The inner side of the block 3 is formed with a concave cutout portion having its wall 7 extend in the same arc throughout. The concave cutout portions in the blocks 2 and 3 extend from the lower to the upper faces thereof. The block 3 is of materially less width than the width of the block 2. The concave cutout portions of the blocks 2 and 3 are oppositely disposed with respect to each other.

Secured upon the upper face of the member 1, is a radius block 8 of semi-circular contour. The block 8 is eccentrically disposed with respect to the wall 4 of the concavity formed in the block 2 and the curved 110

edge of the block 8 opposes said wall 4 and owing to the eccentric disposition of the block 8 with respect to the wall 4, a curved sound branch passage 9 is provided which 5 gradually increases in area from one end towards the other, that is to say it gradually increases in area from its intake towards its outlet end. See Figure 3. The squared edge of the block 8 is arranged in alignment 10 with the inner side edge of the block 2, see Figure 2. Abutting against the squared edge of the block 8 is a pair of wall-forming members 10 and 11 and said member 10 abuts against the inner side of the block 2 and has 15 its inner face form a continuation of the wall 7 of the concavity in the block 3. The wall forming member 11 is positioned at one end centrally of the concavity formed in the block 3 and the said end of said member 20 11 is flush with the inner side edge of the block 3. From the block 3 the members 10 and 11 diverge with respect to each other and the outer face of the member 10 forms a continuation of the curved edge of the 25 block 8. The outer face of the member 11 forms a continuation of the curved edge of the block 8. The members 10 and 11 are constructed of panels standing on edge. Positioned between the members 10 and 11 is 30 a vertically disposed wall-forming member 12 which abuts against the squared edge of the block 8. The members 10, 11 and 12 extend above the blocks 3 and 8 and are of the same height. Secured between the members 10 and 11 is a horizontally disposed upwardly extending inclined wall-forming 35 member 13.

The block 2 is the same height as the block 8, but the block 3 is of greater height 40 than the blocks 2 and 8. Mounted upon the blocks 2 and 8 is a cover member 14 which is common thereto. Mounted on the block 3 is a cover member 15 therefor. Secured to the member 1 and abutting against 45 the inner sides of the blocks 2 and 3 at the outer ends thereof is a vertically disposed wall-forming member 16 which gradually increases in height from the block 2 towards the block 3. Abutting against the cover 50 members 14, 15, as well as the wall forming member 11 and seated on the member 16 is a wall-forming member 17 which inclines from the cover 14 to the cover 15 in an upward direction.

55 Secured upon the upper face of the member 1 and extending from the block 2 and further opposing and spaced from the end 5 of the block 3 is a wall-forming member 18 of materially less height than the height 60 of the block 3 and which gradually increases in height towards the block 2. The member 18 opposes the member 10 and is inclined away therefrom in a direction towards the block 2. Mounted on the member 18 and 65 abutting at one end against the cover mem-

ber 14 and further abutting against the member 10 and block 3 is a wall-forming member 19 which inclines upwards the cover 14.

Arranged between the wall-forming members 10 and 11 and abutting against the member 12 is a radius block 20 having a curved upper face 21. The upper edge of the block 20 is positioned in proximity to the top edges of the members 10, 11 and 12 70 see Figures 1 and 2. The inner face of the member 12 forms a continuation of the upper face of the block 20 see Figure 2.

The base member 1, in connection with one end of the block 3, and the wall-forming members 10, 18 and 19 form a branch sound passage 22 which gradually increases in area from its intake towards its outlet and the outlet of the branch 22 opens into the intake of the branch 9. The base member 1 in connection with the wall-forming members 11, 16 and 17 form a sound branch passage 23 which gradually increases in area from its intake towards its outlet. The outlet of the sound branch passage 9 opens into the intake of the passage 23 and the outlet of the latter opens into the concavity formed in the block 3 and which provides a sound branch passage 24. The wall-forming members 10, 11, 12 and 13 and block 21 in connection with the base member 1 provides a sound branch passage 25 which gradually increases in area from its intake towards its outlet. The passage 24 communicates with the intake in the passage 25 and the outlet of the latter opens into a vertically disposed flaring bell or nozzle 26 which is secured to and seated on the wall-forming members 10, 11, 12 and 13. The outer faces of the sides and one end of the bell 26 form a continuation of the outer faces of the wall forming members 10, 11 and 12. The lower end of the bell 26 is of less width than the length of the wall-forming members 10 and 11 and is flush with one end of said members, and spaced a substantial distance from the other ends thereof.

The sound branch passages 22, 9, 23, 24 and 25 form a sound conducting column or tone chamber which gradually increases in area from its intake towards its outlet end and is of coiled contour. The intake for said column or tone chamber is arranged to one side of the out-take thereof. The sound waves travel in a circuitous direction and gradually expands from the intake to the outlet of said column and the direction in which the sound waves travel is indicated by the arrows in Figure 3.

Secured to the intake end of the sound conducting column or tone chamber, as well as communicating with said intake end, is a phone unit 27 leading from a radio receiving set, not shown.

The sound conducting column or tone

chamber formed by the sound branch passages, is so set up that the sound waves enter in a direction at right angles to the direction in which the sound waves pass 5 from said column or chamber into the bell 26. As the device is constructed of non-resonant wood throughout the reproductions of the sound is not marred in any manner and owing to the manner in which the sound 10 conducting column or tone chamber is arranged it will reproduce the bass or deep notes approximately the same as the true tone thereof or in other words the sound received by the column or tone chamber will 15 be produced approximately the same as when initially broadcast, therefore it is thought that the many advantages of a radio speaker device or horn, in accordance with this invention, can be readily understood, 20 and although the preferred embodiment of the invention is as illustrated and described, yet it is to be understood that changes in the details of construction can be had which will fall within the scope of the invention 25 as claimed.

What I claim is:

A radio speaker comprising a series of wall forming members arranged to provide a coiled sound conducting column or tone chamber including a pair of side portions, a 30 pair of end portions and an intermediate portion extended from one end portion and terminating adjacent the other end portion, one of said end portions being of greater length than the other, one of said side portions being of greater length than the other, 35 said intake positioned at one end of the side portion of greater length and said outlet at one end of said intermediate portion and disposed vertically, and a vertically disposed flaring bell communicating at its lower end with said outlet, and a radius block positioned against the bottom and an end wall of said intermediate portion at the outlet end thereof and formed with a curved upper 40 45 face leading from the bottom to said end wall.

In testimony whereof, I affix my signature hereto.

CLARENCE E. BURK.
